UNITED STATES PATENT OFFICE.

VICTOR E. TOLLEFSON, OF ELK POINT, SOUTH DAKOTA.

DESIGN FOR AN AUTOMOBILE-HORN.

43,806.

Specification for Design.

Patented Apr. 1, 1913.

Application filed January 16, 1913. Serial No. 742,477. Term of patent 7 years.

To all whom it may concern:

Be it known that I, VICTOR E. TOLLEFSON, a citizen of the United States, residing at Elk Point, in the county of Union and State of South Dakota, have invented a new, original, and ornamental Design for an Automobile-Horn, of which the following is a specification, reference being had to the accompanying drawing, forming part thereof.

The figure is a side elevation of an automobile horn showing my new design.

I claim:—

The ornamental design for an automobile horn as shown.

VICTOR E. TOLLEFSON.
